graph Corporation, Cleveland, Ohio, a corpora-
tion of Delaware

Application May 27, 1931, Serial No. 540,259

29 Claims. (Cl. 101—58)

This invention relates to selectors of the kind controlling the operation of printing machines and the like through which devices, having identifying means thereon in the nature of tabs, lacuna, or the like, are sequentially passed. The selector cooperates with the identifying means to separate or otherwise control the devices or to control the operation of the machine. For example, in a printing machine, all of the printing devices passed therethrough are not always used in a printing operation and this is accomplished by selecting which of the printing devices are to be used in a printing operation and which are not to be used or, as it is termed, skipped. Further examples of selection in a printing machine are: The separation or other segregation or identification of the sheets being printed; stopping the operation of the machine under predetermined conditions; controlling the operation of a numbering or dating device; controlling the operation of a signal; controlling the operation of a multiplicating arrangement whereby a number of impressions may be made from the same printing device; controlling the operation of mechanisms operating on the sheets such as, means for orienting the sheets in printing position, means for severing sheets from a web, means for moving the sheets to distribute the impressions, a printing couple acting on the sheets, and other similar mechanisms; controlling the number of sheets to be printed from a selected printing device; controlling an auxiliary printing mechanism; and determining the operating characteristics of the platen or other printing member. The period in the cycle of operation of the machine which may be devoted to the performance of the selection is relatively short and consequently it is of importance that the selection be performed in a rapid manner. Moreover, the detector of the selector must be sensitive to insure accuracy of operation and this is somewhat difficult to attain by reason of the wear to which the detector is subjected and also by reason of the inertia of the detector in the operative movement thereof. One of the salient objects of my invention is to provide a selector embodying a sensitive detector capable of rapid operation.

A variation from the proper position of the identifying means may interfere with the selection, especially where the sensing operation of the detecting means requires that the detecting means contact the identifying means. Hence, another object is to provide a selector which will operate in a positive manner irrespective of slight displacement of the identifying means.

A further object is to use light to control the operation of the selector to thereby increase the speed of operation and to permit detection either during movement of the members carrying the identifying means or while this movement is momentarily arrested.

A still further object is to provide a selector embodying a removable part for determining which of the identifying means are to control the selection.

Still further objects are to provide a selector embodying a minimum number of moving parts so that error by reason of inertia or momentum of moving parts may be eliminated; and which selector will be simple and economical in construction and efficient and positive in operation.

In the accompanying drawings, wherein I have illustrated selected embodiments of my invention,

Fig. 1 is a rear elevational view, in which certain parts are broken away, of a printing machine embodying one form of my invention; 20

Fig. 2 is a sectional view taken substantially on the line 2—2 on Fig. 1;

Fig. 3 is a sectional view taken substantially on the line 3—3 on Fig. 1;

Fig. 4 is a diagrammatic view;

Fig. 5 is a perspective detail view illustrating the printing device and the matrix used therewith;

Fig. 6 is a detail view of a reversing switch;

Fig. 7 is a diagrammatic view illustrating a modified form of the invention;

Fig. 8 is a fragmentary vertical sectional view of a printing device separating arrangement;

Fig. 9 is a vertical sectional view illustrating the operating means for the arrangement shown in Fig. 8;

Fig. 10 is a top plan view of another printing machine with which my invention may be used; 40

Fig. 11 is a vertical sectional view of a portion of the driving mechanism of the machine shown in Fig. 10 and wherein those parts under control of the selector are shown in connected position;

Fig. 12 is a fragmentary vertical sectional view showing part of the operating and control means for the machine illustrated in Fig. 10 and wherein those parts under control of the selector are shown in disconnected position; and

Fig. 13 is a fragmentary view illustrating the operating means for the severing device.

A frequent use of a selector is in a printing machine wherein the selector functions to control the printing operations of the machine. 55

The printing devices are sequentially passed through the machine and have identifying means thereon and the selector cooperates with the identifying means to determine whether a printing device is to be printed or skipped upon movement thereof into printing position.

In Figs. 1 to 7 of the accompanying drawings I have shown my invention in association with a printing machine embodying a main frame 8 having at the upper end thereof a bed 9 on which the printing operations are performed. A bracket on the main frame provides a bearing in which a shaft 10 is journaled and rotatably mounted on this shaft is a flywheel (not shown). Power is transmitted to the flywheel from a suitable source and a clutch structure (not shown) interconnects the flywheel and the shaft. Another clutch structure 11 serves to connect the spur gear 12 to the shaft 10. The spur gear 12 meshes with a spur gear 13 fast on the shaft 14. Also fast on the shaft 14 is a miter gear 15 meshing with a miter gear 16 fixed on the cam shaft 17 journaled in suitable bearings in the frame 8. Fast on the shaft 10 is a miter gear 18 meshing with a miter gear 19 fast on the platen shaft 20, journaled in suitable bearings in the frame 8.

Fast on the shaft 20 is an eccentric 21 (Fig. 3) surrounded by an eccentric strap 22 carrying a connecting rod 23 to which one arm 24 of the plate drive rocker 25 is pivotally connected. At the free end of the rocker 25 is a pawl 26 including a recessed nose 27 adapted to successively engage pins 28 on the sprocket 29 mounted on the shaft 30. Also fast on the shaft 30 is another sprocket (not shown) and the printing device feed chains 31 are directed around these sprockets. As the shaft 20 rotates, a reciprocatory movement is imparted by the eccentric 21 to the connecting rod to so operate the rocker 25 that the recessed nose 27 of the pawl 26 successively engages the pins 28 to impart a step-by-step movement to the sprocket 29. This step-by-step movement imparted to the sprocket is transmitted to the printing device feed chains 31 extending along the printing device guideway. The chains withdraw the printing devices from the magazine M, arranged at one end of the printing device guideways, and move the printing devices, indicated by D, through the guideways into printing position over an anvil such as that indicated by A in Fig. 8.

Impressions are made from the printing device disposed over the anvil by the platen P. After the impression has been made from the printing device positioned on the anvil, the printing device feed chains operate to discharge this printing device into the usual printing device collecting galley.

The platen P is carried by the arm 32 of the rocker 33 pivotally mounted at 34 on the frame 8. The rocker 33 includes two arms 35 and 36 carrying rollers 37 and 38 respectively engaged with the peripheries of conjugated cams 39 and 40 fast on a sleeve 41, surrounding the shaft 20 and adapted to be connected to said shaft, as will be described. When the sleeve is connected to the shaft to rotate therewith the cams 39 and 40 act on the rollers to motivate the rocker 33 and thereby move the platen P into and from printing position to make an impression, through the usual ink ribbon, from the printing device on the anvil.

75 Connection between the sleeve 41 and the shaft

28 is controlled through a clutch including the disc 42 fast on the shaft 20 and having a pawl 43 pivotally mounted thereon. A spring 44 acts on the pawl and urges the nose 45 thereof into engagement with the lug 46 fast on the sleeve 41. In this manner the sleeve 41 is driven with the shaft 20 for power will be transmitted from the shaft to the disc 42 through the pawl 43 to the lug 46.

To disconnect the sleeve from the shaft a throwout arm 47 is provided which engages the tail of the pawl 43 to disconnect the nose 45 from the lug 46. The throwout arm 47 is carried by the rocker 48 pivotally mounted on the shaft 49 carried by the frame 8. The rocker 48 also includes an arm 50 carrying a plate 51 having a notched nose 52. One end of a spring 54 is connected to an anchor 53 on the rocker 48 and the other end of this spring is connected to the spring anchor 55 on the frame 8. The spring 54 acts on the rocker 48 to turn the same in a counter-clockwise direction, as viewed in Fig. 3, about the shaft 49, this action being limited by the engagement of the nut 57 on the restoring rod with the stud 58 on the connecting rod 23 and through which stud the rod 56 is passed. The upper end of the rod 56 is pivotally connected to an arm 59 on the rocker 48. A latch pawl 60 is pivotally mounted on the frame 8 at 61 and has a notch 62 therein into which the notched end 52 on the plate 51 may be extended. Secured to the underside of the latch pawl 60 is a leaf spring 63 carrying a rider 64, engageable with the arcuate face of the index segment 65 pivotally mounted at 66. In the arcuate face of the index segment 65 is a notch 67 into which the rider 64 may move under certain conditions of operation as will be explained. Unitary with the index segment 65 is an arm 68 having a bearing at the free end thereof in which a shaft 70 is journaled.

On this shaft 70 is a knob 71 having indicating indicia thereon which in the present instance comprises the letters P and S. Eccentrically connected to the shaft 70 is the upper end of a link 72, the lower end of which is connected to the arm 73 of the bell crank 74 pivotally mounted at 75 on the frame 8 and including an arm 76 providing an armature for the electro-magnet 77.

When the knob 71 is disposed as illustrated in Figs. 2 and 3 the indicia S is in uppermost position and by reason of the eccentric connection between the shaft 70 and the link 72 the arm 68 will be so positioned that the index segment 65 will be so arranged that the nose of the rider 64 will normally be disposed in the notch 67. However, should the knob 71 be turned so that the indicia P is in uppermost position the just described parts will be so positioned that the nose of the rider 64 will rest on the portion 78 of the index segment 65 at the left hand edge of the notch 67 as viewed in Fig. 3.

When the throwout arm 47 is positioned in the path of the tail of the pawl 43, the nose 45 of the pawl is disengaged from the lug 46 and this occurs when the notched nose 52 on the plate 51 is latched in the notch 62 in the latch pawl 60. When, however, this notched nose is not latched in this notch 62, the throwout arm 47 is held out of the path of the tail of the pawl 43 and consequently the nose 45 is not disengaged from the lug 46. Since the platen P is only operated when the sleeve 41 moves with the shaft 20 and as the sleeve turns with this

shaft only when the nose 45 engages the lug 46 it is apparent that the operation of the platen may be controlled by the engagement of this nose with this lug.

5 The operation of the platen is so controlled in order that only determined of the printing devices moving into printing position will be used in a printing operation. This control of the printing operation is determined from the printing devices which may have tabs T thereon or which may be provided with lacuna or other identifying means. In the illustrated embodiment of the invention the printing device D (Fig. 5) has two tabs T thereon and only printing devices having tabs located similarly to those disclosed will be selected, that is, used in a printing operation when the mechanism is arranged as will now be explained.

Selection has been brought about in the art heretofore by the use of sensing means which contact identifying means on the printing devices but I have supplanted such sensing means or detectors by an improved structure, one form of which is disclosed herein. The selection has 25 usually been determined by the detector of the selector from the printing device immediately behind the one positioned on the anvil. Further, the selection has usually been performed during the time the platen P was making an impression from the printing device on the anvil, that is, the device in printing position, so that in the next cycle of operation of the machine the selector would be set up and could therefore so effect operation that the printing device was 30 printed or skipped, dependent upon its characteristics. For the purpose of describing this invention I show the detector of my selector positioned to similarly cooperate with the printing devices.

40 It is an object of my invention to provide a selector which may be very expeditiously set up. To attain this I provide cooperating guideways 79 in which a control device such as the matrix 80 may be removably mounted. The 45 guideways are so located in the machine that the matrix will be disposed above the tabs or other identifying means on the printing device immediately behind the printing device in printing position, in other words, the printing device 50 in selector position. In the present instance the matrix consists of a flat strip of opaque material in which openings are provided to afford unimpeded light passage at selected positions and the matrix may have as many openings as there 55 are positions for identifying means on the printing devices. If, for example, provision is made on the printing device for twelve tabs, provision will be made in the matrix for twelve openings but it is to be understood that a greater or less 60 number of openings may be provided as required without departing from the purview of my invention.

Light is supplied from a lamp L which has 65 associated therewith, in the present instance, a suitable parabolic reflector 81, this lamp and reflector being mounted at the upper end of a housing 82 and being spaced from the matrix a determined distance. Arranged intermediate the lamp and the matrix is a lens 83, the focal point 70 of which is substantially in the plane of the matrix and this lens directs an elongated beam of light onto the portion of the matrix whereat the openings are to be provided. Below the printing device guideway, in vertical alignment with the matrix 80, I provide a photo-electric cell 84

or other light sensitive means and light passing through the openings in the matrix may pass to this light sensitive means provided it is not blocked off, in the illustrated embodiment of the invention, by tabs T. If there is an opening in the matrix and there is no tab below this opening, the light will pass to and activate the photo-electric cell which is connected in a suitable electric circuit controlling the operation of the electro-magnet 77.

10 One such circuit is disclosed in Fig. 4 and therein line wires 85 and 86 are connected to the primary winding 87 of the transformer 88 which includes a secondary winding 89. The conductor 90 is connected to one end of the 15 secondary winding 89 and to a terminal 115. A conductor 91 is connected to the terminal 115 and to a conductor 91' which is connected to the cathode 92 of the grid-glow tube 93. A conductor 94 is connected to the grid 95 of the tube 20 93 and a conductor 96 interconnects the conductor 91 and the conductor 94. Connected in series in the conductor 96 is a condenser 97 and a resistance 97'. The conductor 94 is also connected to the cathode 98 of the photo-electric cell 84. A conductor 99 is connected to the anode of the photo-electric cell and a conductor 100 is connected to the anode of the grid-glow tube 93. A conductor 101 is connected to the conductors 99 and 100 and to the terminal 116. A conductor 102 is connected to the terminal 116 and to one end of the winding of the relay 103, a conductor 103' having a resistance 104' therein being connected to the other terminal of the winding of the relay 103 and to the other terminal of the secondary winding 89.

25 A characteristic of a grid-glow tube is that, when it is connected in a circuit and the grid thereof is not connected for discharge, the grid will assume a negative potential. To insure 30 that the grid 95 of the tube 93 will have a negative potential, a by-pass is provided between the cathode 92 and the grid through the conductor 91', conductor 96, resistance 97', condenser 97, and conductor 94. When the grid 35 has a negative potential impressed thereon, current will not flow through the grid-glow tube 93 because the negative potential on the grid will oppose any discharge from the cathode. However, when light passes to the photo-electric cell, as when there are no tabs below the 40 openings in the matrix, it will be activated and consequently the circuit will be closed therethrough. The closing of the circuit through the photo-electric cell affords a discharge for the 45 grid 95, as current may flow therefrom through the conductor 94 to the cathode 98 and thence to the anode of the photo-electric cell and through the conductor 99. This discharge causes the grid-glow tube to break down since there 50 will no longer be a negative potential on the grid 95 and consequently a circuit will be established therethrough which will energize the relay 55 103, the armature of which carries a bridge contact 104 that will close the circuit between the contacts 105 and 106.

The contacts 105 and 106 are arranged in a circuit including line wires 107 and 108. The line wire 107 is connected to one end of the winding of the electro-magnet 77 and the line 60 wire 108 is connected to the terminal 105. A conductor 109 interconnects the other end of the winding of the magnet 77 with the contact 106.

65 Consequently, when circuit is closed between the contacts 105 and 106, the electro-magnet 77 70 75

is energized and it therefore attracts the arm 76, which is in the nature of an armature, and turns the bell crank 74 against the action of the spring 110, which normally acts on the bell 5 crank 74 to urge the arm 76 thereof into engagement with the stop pin 111 (Fig. 3) carried by the frame 8. Thus, when the arm 76 is attracted by the electro-magnet 77, the bell crank 74 is turned to rotate the index segment 65 into 10 the position illustrated in Fig. 3 and in so doing the rider 64 is moved out of the notch 67 and rests on the arcuate face of the index segment adjacent the edge of the notch. When the rider 64 is moved out of the notch in this manner, it 15 acts through the leaf spring 63 to so turn the latch pawl 60 that the notch 62 is moved into a position whereat the notched nose 52 may seat and latch therein to thereby position the throw-out arm 47 in the path of the tail of the pawl 20 43 which as previously described, disconnects the nose 45 from the lug 46 and therefore the sleeve 41 does not turn with the shaft 20 and as a result the platen P is not operated and consequently the printing device which has been in selector 25 position will not be printed when it is moved into printing position.

During the cycle of the machine which would normally print from this printing device the connecting rod 23 moves upwardly and moves 30 the restoring rod 56 upwardly, and this imparts movement to the rocker 48 whereby the notched nose 52 will be disengaged from the notch 62 if the parts are not to be latched on the next cycle of operation. However, the selection operation for this cycle of operation will have been performed just prior to this time and if the parts are to remain latched on the next 35 cycle of operation, as when the succeeding printing device is also to be skipped, this upward movement of the restoring rod 56 will not release the parts.

If the printing device in selector position is tabbed in accordance with the disclosure in Fig. 5 it is apparent that there will 45 be tabs below the two openings in the matrix. Consequently, no light will pass to the photo-electric cell and as a result the grid 85 will not be discharged and therefore the circuit to the relay 103 will remain open. Thus, the notched 50 nose 52 will not be latched in the notch 62 and the throwout arm 47 will not engage the tail of the pawl 43 and consequently the sleeve 41 will rotate with the shaft 20 and the platen P will be operated.

55 It may be desirable to reverse the foregoing selection; that is, to skip printing devices having tabs thereon corresponding to the tabs on the printing device illustrated in Fig. 5, and this may be done by rotating the knob 71 to position 60 the indicia P in upper position. The link 72 is eccentrically connected to the shaft 70 and the position of the bell crank 74 is determined. Consequently, when the knob 71 is turned, the relative position of the arm 68 and the index 65 segment 65 is varied. When this is done the rider 64 is normally positioned on the portion 78 and the latch pawl 60 is normally held in an upper position whereat the notched nose 52 will latch in the notch 62 unless the rider 64 moves into the notch 67. When the parts are so arranged the platen P will not be operated unless the relay 77 is energized, for when this occurs, the parts will be moved so that the notch 67 will 70 be below the rider 64 and this will permit the

latch pawl 60 to pivot downwardly as the rider moves into the notch.

It is apparent that passage of light to the photo-electric cell controls the operation of the platen whether the printing devices are to be 5 skipped or printed. The mechanical parts of the selector described herein can only be latched at a certain time in the cycle of operation of the machine but it is to be understood that the use 10 of the described manner of detecting is not limited to a selector of this structure.

Moreover the lamp may be rendered operative only at the time the detection is to be performed and, also the photo-electric cell and the grid glow tube need only be operative while the 15 detection is being performed. Consequently, I provide a timing switch which will render the devices operative only at the time of detection.

One form of timing switch is illustrated in 20 Fig. 3 and includes the spaced contacts 112 and 113. The contacts are closed and opened by an adjusting screw 115 having an insulated end portion 116, this adjusting screw being carried by a lug 114 on the rocker 25. At the time the selection is to be performed, the rocker 25 is so 25 positioned that the lug 114 will move the insulated end portion 116 into engagement with the contact 113 and force the same into engagement with the contact 112 to thereby close the circuit. In the present instance, I provide the contacts 30 112 and 113 in the line wire 85 and the circuit including this wire is closed only while the detection is being performed.

I have described how the selector may be reversed mechanically but the reversing may also be brought about electrically and under certain 35 conditions of operation it may be an advantage to do this, for it would only entail the operation of a switch. In Fig. 7 I have disclosed the electrical connections to be used when such a reverse is desired and in Fig. 6 I have shown one 40 form of switch which may be used to bring about this reverse. In the electrical connections disclosed in Fig. 7, a circuit similar to that shown in Fig. 4 is included and when the various 45 switches are arranged as shown in dotted lines in Fig. 7, the mechanism will function when the photo-electric cell is activated, for under this arrangement circuit through the grid-glow tube is normally open, but when the switches are arranged as shown in full lines in Fig. 7 circuit through the grid-glow tube is normally closed and is opened when light passes through to the 50 photo-electric cell.

The electrical connections disclosed in Fig. 7 55 are to be used with the circuit disclosed in Fig. 4, wires 117 and 131 of these electrical connections being respectively connected to the terminals 115 and 116. A conductor 118 is connected to the line wire 117, the cathode 119 of the grid-glow 60 tube 120 and to a contact 121. A conductor 122 extends between the conductor 118 and the contact 123. A conductor 125 is connected to the grid 124 of the tube 120 and also to a contact 126. A conductor 127 extends between the conductor 125 and the contact 128 and a resistance 129 and a fixed condenser 130 and connected in series in this conductor. The wire 131 extends to a terminal 135. A conductor 132 interconnects the terminal 135 and the anode 134 of the tube. A conductor 136 interconnects the terminal 135 and the contact 137. A conductor 138 interconnects the contacts 139 and 143 and is also connected to the anode 140 of the photo- 70 75

electric cell 141. A conductor 144 interconnects the contact 145 and the contact 146, and a conductor 147 interconnects the conductor 144 and the cathode 148 of the cell 141. Spaced from the contact 124 is a dead contact 149 and this contact is also spaced from the contact 137 (see Fig. 6).

When the various switches are arranged as shown in full lines in Fig. 7, the circuit through the grid-glow tube 120 is normally closed, current flowing from the terminal 115 through conductors 117 and 118 to the cathode 119 and thence through the tube to the anode 134 and through conductors 133 and 131 to the terminal 116 and therefore circuit to the relay 103 is closed which closes the circuit to the electro-magnet 77 and therefore the arm 76 is normally attracted and the devices are operated as previously described.

When, however, light activates the photo-electric cell 141, current flows from the anode 140 through the conductor 138, contact 143, switch blade 150, contact 126, conductor 125, to the grid 124 to thereby impress a negative potential on the grid 124 which opposes discharge from the cathode 119 and consequently the circuit through the grid-glow tube is opened. Connection between the anode 140 and the conductor 131 is broken by reason of the fact that the switch blade 153 is disposed on the dead contact 149. The cathode 119 is connected to the cathode 148 through conductor 118, contact 121, switch blade 152, contact 146, and conductor 147. A by-pass is provided between the grid 124 and the conductor 131 so that the current value of the impressed negative potential may be kept at a minimum, this by-pass being afforded by the conductor 125, condenser 130, resistance 129, conductor 127, contact 128, switch blade 151, contact 135 to conductor 131.

However, when the switches are arranged in the dotted-line position, the mechanism is arranged as shown in Fig. 4 and it functions in the manner described, the electrical connections being as follows: the grid 124 is connected to the cathode 148 through the conductor 125, contact 126, switch blade 150, contact 145, conductor 144, and conductor 147. A by-pass between the grid 124 and the cathode 119 is provided by conductor 125, condenser 130, resistance 129, conductor 127, contact 128, switch blade 151, contact 123, conductor 122, and conductor 118. In order that the cathode 119 will not be connected to the cathode 148 the switch blade 152 is moved into the dotted-line position and engages the dead contact 149. The anode 140 is connected to the conductor 131 through conductor 138, switch blade 153, and conductor 136, and it is therefore apparent that the electrical connections in this instance are like those disclosed in Fig. 4 and consequently the device will function in a like manner.

In the foregoing description I have described a selector controlling the printing operation in a printing machine. I have previously stated, however, that the invention is not necessarily limited to this control of the printing operation and also that the invention is not limited to use with a printing machine. It is often desirable, in machines of the kind through which devices having identifying means thereon are passed, to separate the devices. For example, in the patent to Joseph S. Duncan, No. 1,299,437, patented April 8, 1919, there is shown a printing machine wherein the printing devices are passed into selected gal-

leys after they have passed through printing position in the machine and this separation of the printing devices is controlled by a mechanical detector acting on identifying means on the printing devices. It is within the ambit of my invention to substitute a detecting arrangement, similar to that which I have described herein, for the mechanical detector shown in that patent. Furthermore, this separating of the devices having identifying means thereon may be done prior to passage of the devices into operative position in the machine.

An arrangement such as that disclosed in the aforesaid Duncan Patent 1,299,437 is fragmentally illustrated in Figs. 8 and 9 wherein a chute 160 is shown immediately forward of the anvil A. The printing devices D pass into the chute from the anvil, on which the printing devices are positioned when impressions are made therefrom by the platen P in the manner previously explained.

A gate 161 is provided in the chute 160 and when this gate is in the position shown in Fig. 8 the printing devices pass thereover and into the branch chute 162 to be collected in the tray or galley 163. When, however, the gate 161 is moved to the other side of the chute 160 the printing devices pass through the portion 160' of this chute to be collected in the tray or galley 164. The galleys 163 and 164 are removably supported in the machine in a suitable manner so that when one of these trays is filled with printing devices it may be removed and another tray is then substituted therefor.

A packer frame 165 of the kind well understood in the art is provided which includes depending fingers as 166. As each printing device is delivered into the tray 164 the packer frame is operated to force the printing device rearwardly in the tray. The packer frame is pivotally mounted at 167 and is also provided with depending fingers 168 which force the printing devices delivered into the tray 163 rearwardly in this tray. The packer frame 165 as is well understood in the art operates in timed relation with the delivery of the printing devices into the trays.

The rod 169, on which the gate 161 is mounted, is provided at one end with a yoke 170 (Fig. 9). An arm 171 is loosely mounted on the rod 169 between the arms of the yoke. An adjustable screw 172 in one arm of the yoke engages the arm 171 and a spring 173 is disposed between the arm 171 and the other arm of the yoke. A spring 174 is connected to the arm 171 and to the frame of the machine and normally holds the rod 169 and consequently the gate 161 in the position indicated in Fig. 8.

In the illustrated form of the invention it is desired to pass all printing devices that are to be used again through the chute 162 into the tray 163 and to deflect those printing devices that are not to be used again into the portion 160' of the chute 160 and thence into the tray 164. Obviously this plan may be reversed if desired. In the machine as shown, however, it is necessary to shift the gate 161 after every impression taken from a printing device which is to be deposited in the tray 164. The gate is left in its normal position shown in Fig. 8 after each impression from the printing device which is to be deposited in the tray 163. This is under control of the selector mechanism of this invention and in the manner previously described the electro-magnet 77 is energized when the selector cooperates with printing devices D having tabs T in a predeter-

mined position. All printing devices having tabs T in a predetermined position so as to effect energization of the electro-magnet 77 are delivered into the tray 164. All other printing devices are 5 delivered into the tray 163. This operation may, of course, be reversed if desired. Hence whenever the selector mechanism, which may be located for the purpose of controlling the gate 161 at printing position, cooperates with a printing device 10 having a tab T in a predetermined position the gate 161 is shifted.

To this end a shaft 175 is mounted in the frame of the machine and is driven from the drive shaft 20 in synchronism therewith by a chain 176 directed about sprockets (not shown) on the shafts 20 and 175. A collar 177 is fast on the shaft 175 and a cam 178 is rotatably mounted on the shaft adjacent said collar. Normally a dog 179 pivotally mounted on the cam 178 is seated in the notch 180 in the collar 177 under the action of the spring 181. The dog is unseated from the notch 180 by engagement thereof with the throw-out arm 186. Upon each revolution of the shaft 20 the shaft 175 makes a revolution as does the 25 cam 178 when the dog is seated in the notch. The cam 178 engages a roller 182 on the arm 171 and is provided with a high portion followed by a slight depression. As this high portion passes the roller 182 the arm 171 causes the yoke 170 30 to swing, thus moving the gate 161 to the right as viewed in Fig. 8. The cam is timed, however, so that normally the roller 182 rests on a low portion thereof when a printing device reaches the delivery end of the printing device guideway 35 and therefore the printing device will normally pass through the chutes 160 and 162 into the tray 163.

A rocker 183 pivoted at 184 on the frame of the machine has a roller 185 thereon that is normally 40 held in engagement with the throwout arm 186 by the spring 187. A link 188 is connected to the rocker 183 and to the free end of the arm 72 of the bell crank 74, the arm 76 of which bell crank is the armature of the electro-magnet 77.

45 Thus, whenever the electro-magnet 77 is energized the armature 76 thereof is attracted whereupon the bell crank 74 pivots, and this movement is transmitted from arm 72 thereof through link 188 to rocker 183 which thereupon so pivots 50 that the roller 185 acts on the throwout arm 186 to so position this throwout arm that it engages the tail of the dog 179 which is thereupon unseated from the notch 180. This uncoupling occurs just as the roller 182 drops into the depression following the high point of the cam 178 and the gate 161 is thereupon moved to the right, as viewed in Fig. 8, and held there during the following revolution of the shaft 20, that is to say, while a printing device is discharged into the 55 chute 160. The printing device in this instance therefore passes through the portion 160' of the chute into the tray 164.

If in the next cycle of operation the electro-magnet 77 is not energized the throwout arm 186 60 will not engage the tail of the dog 179 and the pawl will therefore reseat in the notch 180 and again start rotation of the cam 178 which will 65 again cause the gate 161 to be seated in its normal position shown in Fig. 8. If, however, the 70 succeeding printing device is so tabbed that it effects energization of the electro-magnet 77, the throwout arm again engages the tail of the dog 179 and it is prevented from seating in the notch 75 180 wherefore the gate 161 remains positioned to

direct the succeeding printing device into the tray 164.

Thus the mechanism disclosed in the Duncan Patent 1,299,437 can be readily controlled by the selector disclosed herein, it only being necessary to supplant the mechanically operating devices of the Duncan patent by devices controlling the electro-magnet 77. 5

In the application of Emmett C. Hartley, Serial No. 535,818, filed May 8, 1931, now Patent 2,002,737, patented May 28, 1935, there is shown the control of a number of mechanisms in a printing machine by a detector cooperating with identifying means on the printing devices. In this application a selector having features in common 10 with the selector disclosed in the present application is described and it is therefore readily apparent that the detector of the selector of that application may easily be supplanted by the detector shown herein, including the light sensitive 15 means. 20

The machine shown in the aforesaid Hartley application is of the kind wherein bill sections such as utility bills, insurance notices and the like are printed. In machines of the kind therein 25 illustrated the bill sections are severed from a web and impressions are usually made on both faces thereof from permanent printing forms in the machine. Impressions are also made on the bill sections from printing devices sequentially 30 passed through printing position in the machine. The printing devices, as in previously described forms of the invention, are withdrawn from a magazine in the machine and passed into printing position. These printing devices like those 35 previously described bear identifying means such as tabs and the machine is under control of a selector responsive to such identifying means on the printing devices.

In the normal operation of the machine the 40 successive passage of the bill sections and the sequential passage of the printing devices are in timed relation which must be maintained to insure proper operation of the machine. Thus if a printing device is not to be used in a printing 45 position upon movement thereof into printing position, the printing device feeding mechanism must be operated in a normal manner while operation of the other mechanisms is interrupted.

The machine illustrated in the aforesaid Hartley application is of the kind disclosed in another 50 co-pending Hartley application, Serial No. 459,599, filed June 6, 1930, now Patent 2,041,183, patented May 19, 1936, to which reference may be made for the details of construction of the 55 machine.

The machine, however, as illustrated in Figs. 10, 11, 12 and 13 hereof includes a printing couple embodying a printing cylinder 190 which, in the present instance, has a platen cylinder (not shown) in vertical alignment therewith. A web is withdrawn from a suitably supported roll and passed through this printing couple and thence to a pair of vertically aligned feeding rollers, the roller 191 of which is illustrated in Fig. 10. The web passes from the feeding rollers as 191 through a severing device comprising a stationary knife 192 and a movable knife 193. 60

65 Power is supplied to the machine from an electric motor or other source of power through a belt 194 directed about a flywheel 195 that is freely rotatable on the drive shaft 196, said flywheel being connected to said shaft through a manually controlled main clutch 197. When this clutch is engaged the machine is set in operation. 70 75

A bevel gear 198 on the drive shaft 196 meshes with a bevel gear 199 on the shaft 20a which corresponds to the shaft 20 in the form of the invention illustrated in Figs. 1 to 7. The various devices provided in the machine are operated from the shafts 196 and 20a.

The printing devices in the form of the invention are stored in a magazine M and are withdrawn therefrom by a feeding mechanism operated from the shaft 20a. An eccentric 21a is fast on the shaft 20 and is surrounded by an eccentric strap 22a carrying a connecting rod 23a to which the arm 24a of the printing device drive rocker 25a is pivotally connected. This drive rocker 25a corresponds to the drive rocker 25 shown in Fig. 2 and functions in like manner to bring about step by step advancing of the printing devices.

The platen P' is carried by an arm corresponding to the arm 32 (Fig. 2) of a rocker like the rocker 33. This rocker includes two arms like the arms 35 and 36 that carry rollers like the rollers 37 and 38, which rollers are respectively engaged with the peripheries of conjugated cams like the cams 39 and 40, which cams are fast on a sleeve 41a that corresponds to the sleeve 41. The sleeve 41a is disposed about the shaft 20a and is adapted to be connected thereto through a pawl like the pawl 43 which is engaged and disengaged under control of a throwout arm 47a which is similar to the throwout arm 47 (Fig. 3). In other words, when the throwout arm 47a is moved inwardly to the position in which it is shown in Fig. 12, it engages the tail of a pawl 35 and interrupts operation of the platen P'.

After a sheet has been stopped by the last of the stop fingers 201 it moves into a printing couple C mounted on the frame of the machine and from this printing couple the sheets are discharged into a suitable collecting receptacle. The printing couple C may be of the kind, for example, disclosed in the application of Curtis George Kranz, Serial No. 404,092, filed November 1, 1929, now Patent 1,955,814, patented April 24, 1934. It is to be understood, however, that any suitable printing couple may be used.

It is therefore apparent that a roll of paper may be mounted at one end of the machine and that a web may be led therefrom to be passed through a printing couple wherein impressions are made at spaced intervals on one face of the web. From this printing couple the web is directed through a pair of feeding rollers and a severing device and this severing device is operated to divide the web into sheets intermediate the impressions made thereon by the printing couple, this being so effected that the impressions are neatly oriented on one face of each of the sheets. The severed sheets are then moved along into printing position below a platen which makes impressions from printing devices on the face of the sheet opposite that from which impressions were made by the printing couple.

Prior to the time the web is severed from the sheet it may be scored to divide it into a plurality of sections such as a main body and one or more stubs. The platen is operated to make an impression from each of said sections, the stop fingers 201 positioning the sheet for this purpose. After the platen has made an impression on each section of a sheet the sheet is then passed to the printing couple C wherein an impression is made on the same face of the sheet as that on which impressions were made by the

platen, the sheets then being discharged into the collecting receptacle.

A step by step movement is imparted to the web to feed it through the severing device so that sheets of predetermined width are severed therefrom. Such step by step movement is imparted to the web by the feeding rollers as 191.

These rollers are in clamping engagement with each other so as to tightly clamp the web therebetween and are interconnected by pinions having a one-to-one ratio so that when power is supplied to one of the rollers the other will be driven in synchronism therewith. To this end a pinion 202 is freely mounted on the shaft of one of the rollers and through a suitable clutch device 203 imparts rotative movement to the rollers when driven in one direction by the gear segment 204. The gear segment 204 is operated by a crank 205 which receives movement from a shaft 206 which has a bevel gear 207 that meshes with a bevel gear 208 on the jack shaft 209. This shaft 209 is driven from the drive shaft 196 in the following manner:

A clutch, generally indicated by 210 (Fig. 10) is mounted on the shaft 196. This clutch includes a collar 211 (Fig. 11) that is fast on the shaft 196 and which has a notch 212 in the periphery thereof. A gear 213 is rotatably mounted on the shaft 196 and carries a pawl 214 that is normally seated in the notch 212 and so long as this pawl is seated in this notch rotative movement is imparted to the gear 213 which meshes with a gear 215 fast on the shaft 209. Thus so long as the pawl 214 is seated in the notch 212 the shaft 209 rotates with the shaft 196. The gears 213 and 215 have a one-to-one ratio and therefore the shaft 209 rotates in synchronism with the shaft 196 as does the shaft 20a and the shaft 206, which latter shaft, as stated, is driven from the shaft 209.

The severing device consisting of the knives 192 and 193 is operated from the shaft 206 by a cam 216 (Fig. 13) which serves to reciprocate a bell crank 217, one arm of said bell crank being connected to the movable knife 193 through a link 218. This arrangement functions to lower the knife 193 and sever a sheet from the web intermediate feeding operations of the rollers as 191.

The printing couple including the cylinder 190 is also operated from the shaft 206, a gear 219 being fast on the shaft 206 and meshing with a gear 220 which in turn is connected to a gear 221 that meshes with a gear (not shown) on the shaft carrying the platen cylinder of the printing couple, and this gear meshes with a gear 222 on the shaft carrying the printing cylinder 190.

It will therefore be seen that the printing couple including the printing cylinder 190, the feeding rollers including the roller 191, and the severing device including the movable knife 193 are all operated from the shaft 209, the operation of which in turn is controlled by the pawl 214.

The stop fingers 201 are operated by a cam shaft 17a (Fig. 12). In each cycle of operation the cam shaft 17a makes as many revolutions as there are sections on the sheets S being printed in the machine. Thus if the sheets S are divided into three sections the cam shaft 17a makes three revolutions in each cycle. The cam shaft 17a is also driven from the shaft 209, it being provided with a bevel gear 223 that meshes with a bevel gear 224 fast on the shaft 209, the ratio between these gears being such as to bring 75

about the required number of operations of the cam shaft 17a in a cycle of operation of the machine.

The belts 200 are also driven from the shaft 209, a gear 225 being fast on the shaft 209 which, through the gear train 226, drives the shaft 227 on which the pulleys, about which the belts 200 are directed at one end of the machine, are passed (see Fig. 11).

10 It has been explained that the platen is to make an impression from each printing device in printing position selected to be printed onto each section of each sheet. Thus if the sheets are divided into three sections the three impressions are to be made from each printing device fed into printing position and therefore in two cycles of operation of the machine the means effecting operation of the rocker 25a are rendered inoperative.

20 It has been explained that the connecting rod 23a (Fig. 12) is connected to the arm 24a. This connection includes a sleeve 228 into which the connecting rod 23a extends. A spring urged pawl 229 is mounted on this sleeve and normally 25 seats on a shoulder on the connecting rod 23a. A pin 230 is provided on this pawl and is engageable by the arm 231 of the rocker, generally indicated by 232, which also includes an arm 233 having a roller 234 thereon engageable with 30 a cam 235 on the cam shaft 17a. The cam 235 includes a flattened portion which, during the last impression from a printing device, engages the roller 234 and thereupon so positions the arm 231 that it is out of the path of the pin 230 35 which enables the pawl 229 to engage the shoulder on the connecting rod 23a, and therefore in this cycle of operation the drive rocker 25a will be operated to advance the printing devices.

If a printing device fed into printing position 40 following such operation of the rocker 25a is to be printed, the cam shaft 27a rotates in the next cycle of operation and the cam 235 thereupon so positions the arm 231 that the pawl 229 is held from connection with the shoulder on 45 the connecting rod 23a until the cycle of operation in which the last impressions are made from this printing device. If, however, the printing device newly fed into printing position is not to be printed, the cam shaft 17a does not rotate 50 and the printing device newly fed into printing position is passed therefrom without an impression being made therefrom.

Thus so long as the pawl 214 is seated in the notch 212 the cam shaft 17a is operated as well 55 as the printing couple, the feeding rollers, the severing device and the conveyor belts, but when the pawl is unseated these mechanisms do not operate.

Whether or not the pawl 214 remains seated in 60 the notch 212 depends upon the position of the throwout arm 236 (Fig. 11) and the positioning of this throwout arm is under control of this selector. An arm 237 is connected to the throwout arm 41a and is movable therewith into alternate positions. The arm 237 has a depending portion 238 on which a roller 239 is mounted. The roller 239 is engageable with a roller 240 on the throwout arm 236 which is pivotally mounted 65 on the frame at 241. When the throwout arm 70 41a is positioned to disconnect the sleeve 41a from the shaft 20a and thereby interrupt operation of the platen, the arm 237 is so positioned that the roller 239 engages the roller 240 and so positions the throwout arm 236 that the pawl 75 214 is unseated from the notch 212. Thus when-

ever the platen is rendered inoperative, the means operated from the shaft 209 through the pawl 214 are likewise rendered inoperative.

In the aforesaid Hartley Patent 2,002,737 the 5 position of the throwout arm 41a is under control of a mechanical selector. In place of the mechanical selector shown in that invention, a selector like that disclosed herein may be used and positioning of the throwout arm 41a may be brought about by such a selector.

10 Thus an electro-magnet like the electro-magnet 77 is provided which is controlled in the same manner as the electro-magnet 77. The armature 76 of this electro-magnet is connected to one arm of a bell crank 74 and one end of a link 250 is connected to the arm 72 of this bell crank. When the electro-magnet 77 is energized under conditions similar to those previously described, the armature 76 thereof is attracted which rocks the bell crank 74 and the arm 72 thereof through 15 the link 250 which thereupon so positions the throwout arms 41a, 236 that the platen and the devices operated from the shaft 209 are rendered inoperative. This operation is timed to occur only during the cycle in which the last impression is made from a printing device and in this manner all mechanisms in the machine except 20 the printing device feeding means are rendered operative. The printing device feeding means remains operative and advances the succeeding 25 printing device into printing position in the succeeding cycle of operation when a printing device is to be skipped. All parts remain in the position in which they were stopped and therefore the timed relation therebetween is maintained 30 just as is effected in the machine disclosed in the aforesaid Hartley patent.

35 Thus the mechanism disclosed in the Hartley Patent 2,002,737 can be readily controlled by the selector disclosed herein, it only being necessary 40 to supplant the mechanically operating devices of the Duncan patent by devices controlling the electro-magnet 77.

45 In the foregoing description I have described the use of a photo-electric cell in connection with a grid-glow tube but it is to be understood that the invention is not limited to the use of such a tube for an ordinary audion or other suitable amplifying means may be employed. Moreover, the invention is not limited to the use of a photo-electric cell as a selenium cell or other light sensitive means may be used.

50 In the described embodiments of the invention the movement of the printing devices is arrested during the time the selection is being performed but manifestly the detection may be carried out while the printing devices or other devices carrying identifying means are in motion.

55 While I have illustrated and described a selected form of construction for my invention it is to be understood that this is capable of variation and modification and I therefore do not wish to be limited to the precise details set forth but desire to avail myself of such changes and alterations as fall within the spirit and scope of 60 the following claims.

I claim:

65 1. In a printing machine, operative means, a printing device guideway including a selector position, means sequentially moving printing devices through said guideway and the selector position therein, said printing devices having a plurality of identifying means positions distributed thereover whereat identifying means may be provided to classify said printing devices, and 70 75

means to regulate the operation of said operative means in accordance with the classification of the printing device disposed at selector position and embodying detecting means including a source of light, light sensitive means adapted to be influenced by light from said source, means directing a beam of light from said source to selector position and concentrating said beam on the identifying means positions on the printing device at selector position, and means to control the passage of the beam of light to the identifying means positions on the printing device at selector position whereby only selected of said positions are effective in the regulation of the operation of said operative means.

2. In a printing machine, operative means, a printing device guideway including a selector position, means sequentially moving printing devices through said guideway and the selector position therein, said printing devices having a plurality of identifying means positions distributed thereover whereat identifying means may be provided to classify said printing devices, and means to regulate the operation of said operative means in accordance with the classification of the printing device disposed at selector position and embodying detecting means including a source of light positioned on one side of said printing device guideway, light sensitive means adapted to be influenced by light from said source and positioned on the other side of said printing device guideway, means directing a beam of light from said source to selector position and concentrating the beam on the identifying means positions on the printing device at selector position, and means interposed between the printing device at selector position and the beam directing and concentrating means to control the passage of the beam of light to the identifying means positions on the printing device at selector position whereby only selected of said positions are effective in the regulation of the operation of said operative means.

3. In a printing machine, operative means, a printing device guideway including a selector position, means sequentially moving printing devices through said guideway and the selector position therein, said printing devices having a plurality of identifying means positions distributed thereover whereat identifying means may be provided to classify said printing devices, and means to regulate the operation of said operative means in accordance with the classification of the printing device disposed at selector position and embodying detecting means including a source of light, light sensitive means adapted to be influenced by light from said source, means directing a beam of light from said source to selector position and concentrating said beam on the identifying means positions on the printing device at selector position, means to control the passage of the beam of light to the identifying means positions on the printing device at selector position whereby only selected of said positions are effective in the regulation of the operation of said operative means, and means for rendering said light sensitive means operative at predetermined times in the operation of said machine.

4. In a printing machine, a printing device guideway including selector and printing positions, means sequentially moving printing devices through said guideway and the selector and printing positions therein, impression means for making impressions from the printing devices disposed in printing position, said printing devices

having a plurality of identifying means positions distributed thereover whereat identifying means may be provided to classify said printing devices, and means to regulate the operation of said impression means whereby only printing devices having a predetermined classification will effect operation of said impression means, said regulating means embodying detecting means including a source of light, light sensitive means adapted to be influenced by light from said source, means directing a beam of light from said source to selector position and concentrating said beam on the identifying means positions on the printing device at selector position, and means to control the passage of the beam of light to the identifying means positions on the printing device at selector position to thereby select the predetermined classification of printing devices adapted to be effective in the regulation of the operation of said impression means.

5. In a printing machine, operating means, a printing device guideway including selector and printing positions, means sequentially moving printing devices through said guideway and the selector and printing positions therein and operated by said operating means, a platen for making impressions from the printing devices disposed in printing position and operated by said operating means, said printing devices having a plurality of identifying means positions distributed thereover whereat identifying means may be provided to classify said printing devices, and means operable in timed relation with the operating means to regulate the operation of said platen whereby only printing devices having a predetermined classification will effect operation of said platen, said regulating means embodying detecting means operable independently of the operating means and including a source of light positioned on one side of said printing device guideway, light sensitive means adapted to be influenced by light from said source and positioned on the other side of said printing device guideway, means directing a beam of light from said source to selector position and concentrating the beam on the identifying means positions on the printing device at selector position, and means interposed between the printing device at selector position and the beam directing and concentrating means to control the passage of the beam of light to the identifying means positions on the printing device at selector position to thereby select the predetermined classification of printing devices adapted to be effective in the regulation of the operation of said platen.

6. In a printing machine, operating means, a printing device guideway including selector and printing positions, means sequentially moving printing devices through said guideway and the selector and printing positions therein and operated by said operating means, a platen for making impressions from the printing devices disposed in printing position and operated by said operating means, said printing devices having a plurality of identifying means positions distributed thereover whereat identifying means may be provided to classify said printing devices, and means operable in timed relation with the operating means to regulate the operation of said platen whereby only printing devices having a predetermined classification will effect operation of said platen, said regulating means embodying detecting means operable independently of the operating means and including a source of light positioned on one side of said printing device guide- 75

way, light sensitive means adapted to be influenced by light from said source and positioned on the other side of said printing device guideway, means directing a beam of light from said source to selector position and concentrating the beam on the identifying means positions on the printing device at selector position, supporting means disposed between the printing device at selector position and the beam directing and concentrating means, and a member removably mounted in said supporting means and adapted to control the passage of the beam of light to the identifying means positions on the printing device at selector position to thereby select the predetermined classification of printing devices adapted to be effective in the regulation of the operation of said platen.

7. In a printing machine, operating means, operative means operable by said operating means, a printing device guideway including a selector position, means sequentially moving printing devices through said guideway and the selector position therein, said printing devices having a plurality of identifying means positions distributed thereover whereat identifying means may be provided to classify said printing devices, means operable in timed relation with the operating means to regulate the operation of said operative means in accordance with the classification of the printing device disposed at selector position and embodying detecting means operable independently of said operating means and including a source of light, light sensitive means adapted to be influenced by light from said source, means directing a beam of light from said source to selector position and concentrating said beam on the identifying means positions on the printing device at selector position, and means to control the passage of the beam of light to the identifying means positions on the printing device at selector position whereby only selected of said positions are effective in the regulation of the operation of said operative means, and means in the regulating means independent of the detecting means and operable to reverse the operation of the regulating means.

8. In a printing machine, operating means, operative means operable by said operating means, a printing device guideway including a selector position, means sequentially moving printing devices through said guideway and the selector position therein, said printing devices having a plurality of identifying means positions distributed thereover whereat identifying means may be provided to classify said printing devices, means operable in timed relation with the operating means to regulate the operation of said operative means in accordance with the classification of the printing device disposed at selector position and embodying a settable member for determining the operation thereof, said regulating means also embodying detecting means operable independently of said operating means and including a source of light, light sensitive means adapted to be influenced by light from said source, means directing a beam of light from said source to selector position and concentrating said beam on the identifying means positions on the printing device at selector position, and means to control the passage of the beam of light to the identifying means positions on the printing device at selector position whereby only selected of said positions are effective in the regulation of the operation of said operative means, and means for adjusting said

settable member to determine the operation of said regulating means.

9. In a printing machine, operating means, operative means operable by said operating means, a printing device guideway including a selector position, means sequentially moving printing devices through said guideway and the selector position therein, said printing devices having a plurality of identifying means positions distributed thereover whereat identifying means may be provided to classify said printing devices, and means operable in timed relation with the operating means to regulate the operation of said operative means in accordance with the classification of the printing device disposed at selector position and embodying detecting means operable independently of said operating means and including a source of light, light sensitive means adapted to be influenced by light from said source and connected in an electric circuit, means directing a beam of light from said source to selector position and concentrating said beam on the identifying means positions on the printing device at selector position, means to control the passage of the beam of light to the identifying means positions on the printing device at selector position whereby only selected of said positions are effective in the regulation of the operation of said operative means, and means in the circuit including the light sensitive means for reversing the connection of said light sensitive means in said circuit whereby operation of the reversing means effects operation of the regulating means in a manner opposite to the operation of the regulating means prior to the operation of said reversing means.

10. In a printing machine, operating means, operative means operable by said operating means, a printing device guideway including a selector position, means sequentially moving printing devices through said guideway and the selector position therein, said printing devices having a plurality of identifying means positions distributed thereover whereat identifying means may be provided to classify said printing devices, and means operable in timed relation with the operating means to regulate the operation of said operative means in accordance with the classification of the printing device disposed at selector position and embodying an electric circuit having electromagnetic means therein, and detecting means operable independently of said operating means and including a source of light, light sensitive means connected in parallel with said electromagnetic means and adapted to control operation of said electro-magnetic means and adapted to be influenced by light from said source, means for directing a beam of light from said source to selector position and concentrating said beam on the identifying means positions on the printing device at selector position, and means to control passage of the beam of light to the identifying means positions on the printing device at selector position whereby only selected of said positions are effective in regulating the passage of light to said light sensitive means.

11. In a printing machine, operating means, operative means operable by said operating means, a printing device guideway including a selector position, means sequentially moving printing devices through said guideway and the selector position therein, said printing devices having a plurality of identifying means positions distributed thereover whereat identifying means may be provided to classify said printing devices, means operable in timed relation with the operating means

to regulate the operation of said operative means in accordance with the classification of the printing device disposed at selector position and embodying an electric circuit having electromagnetic means therein, and detecting means operable independently of said operating means and including a source of light, light sensitive means connected in parallel with said electro-magnetic means and adapted to control operation of said electro-magnetic means and adapted to be influenced by light from said source, means for directing a beam of light from said source to selector position and concentrating said beam on the identifying means positions on the printing device at selector position, and means to control passage of the beam of light to the identifying means positions on the printing device at selector position whereby only selected of said positions are effective in regulating the passage of light to said light sensitive means, and means operable from the printing device moving means for regulating current flow through said circuit to thereby time the operation of said circuit.

12. In a printing machine, a printing device guideway including selector and printing positions, means sequentially moving printing devices through said guideway and the selector and printing positions therein, a platen for making impressions from the printing devices disposed in printing position, said printing devices having a plurality of identifying means positions distributed thereover wherewith identifying means may be provided to classify said printing devices, a shaft for operating the printing device moving means and the platen, means for latching said platen to said shaft, and means for regulating the engagement of said latch and including an electric circuit having an electromagnet therein, detecting means operable independently of said shaft and including a source of light, light sensitive means included in said electric circuit and adapted to be influenced by light from said source, means directing a beam of light from said source to selector position and concentrating said beam on the identifying means positions on the printing device at selector position whereby only selected of said positions are effective in the regulation of the passage of light to said light sensitive means.

13. In a printing machine, a printing device guideway including selector and printing positions, means sequentially moving printing devices through said guideway and the selector and printing positions therein, a platen for making impressions from the printing devices disposed in printing position, said printing devices having a plurality of identifying means positions distributed thereover wherewith identifying means may be provided to classify said printing devices, a shaft for operating the printing device moving means and the platen, means for latching said platen to said shaft, and means for regulating the engagement of said latch and including an electric circuit having an electromagnet therein, detecting means operable independently of said shaft and including a source of light, light sensitive means included in said electric circuit and adapted to be influenced by light from said source, means directing a beam of light from said source to selector position and concentrating said beam on the identifying means positions on the printing device at selector position, and means to control the passage of the beam of light to the identifying means positions on the printing device at selector position whereby only selected of said positions are effective in the regulation of light passage to said light sensitive means, passage of light to said light sensitive means discharging the negative potential on said member and establishing flow of current in said circuit.

14. In a printing machine, operating means, operative means operable by said operating means, a printing device guideway including a selector position, means sequentially moving printing devices through said guideway and the selector position therein, said printing devices having a plurality of identifying means positions distributed thereover wherewith identifying means may be provided to classify said printing devices, means operable in timed relation with the operating means to regulate the operation of said operative means in accordance with the classification of the printing device disposed at selector position and embodying an electric circuit having a member therein on which a negative potential is adapted to be impressed, and detecting means operable independently of said operating means and including a source of light, light sensitive means adapted to regulate the negative potential impressed on said member and being adapted to be influenced by light from said source, means directing a beam of light from said source to selector position and concentrating said beam on the identifying means positions on the printing device at selector position, and means to control passage of the beam of light to the identifying means positions on the printing device at selector position whereby only selected of said positions are effective in the regulation of light passage to said light sensitive means, passage of light to said light sensitive means discharging the negative potential on said member and establishing flow of current in said circuit.

15. In a printing machine, operating means, operative means operable by said operating means, a printing device guideway including a selector position, means sequentially moving printing devices through said guideway and the selector position therein, said printing devices having a plurality of identifying means positions distributed thereover wherewith identifying means may be provided to classify said printing devices, means operable in timed relation with the operating means to regulate the operation of said operative means in accordance with the classification of the printing device disposed at selector position and embodying an electric circuit having a member therein on which a negative potential is adapted to be impressed to prevent current flow through said circuit, and detecting means operable independently of said operating means and including a source of light, light sensitive means adapted to impress a negative potential on said member to interrupt flow of current in said circuit and adapted to be influenced by light from said source, means directing a beam of light from said source to selector position and concentrating said beam on the identifying means positions on the printing device at selector position, and means to control passage of the beam of light to the identifying means positions on the printing device at selector position whereby only selected of said positions are effective in

- the regulation of light passage to said light sensitive means.
16. In a printing machine, operating means, operative means operated by said operating means, a printing device guideway including a selector position, means sequentially moving printing devices through said guideway and the selector position therein, said printing devices having a plurality of identifying means positions distributed thereover whereat identifying means may be provided to classify said printing devices, and selector means operable in timed relation with the operating means to regulate operation of said operative means in accordance with the classification of the printing device disposed at selector position and embodying detecting means operable independently of the operating means and including a source of light, and light sensitive means adapted to be influenced by light from said source, the identifying means on the printing device at selector position regulating the passage of light to said light sensitive means and thereby determining the operation of said selector means.
17. In a printing machine, operating means, operative means operated by said operating means, a printing device guideway including a selector position, means sequentially moving printing devices through said guideway and the selector position therein, said printing devices having a plurality of identifying means positions distributed thereover whereat identifying means may be provided to classify said printing devices, and selector means operable in timed relation with the operating means to regulate operation of said operative means in accordance with the classification of the printing device disposed at selector position and embodying detecting means operable independently of the operating means and including a source of light, light sensitive means adapted to be influenced by light from said source, the identifying means on the printing device at selector position regulating the passage of light to said light sensitive means and thereby determining the operation of said selector means, and means controlling the passage of light to the identifying means on the printing device at selector position whereby only predetermined of said identifying means are effective in determining the operation of said selector means.
18. In a printing machine, operating means, operative means operated by said operating means, a printing device guideway including a selector position, means sequentially moving printing devices through said guideway and the selector position therein, said printing devices having a plurality of identifying means positions distributed thereover whereat identifying means may be provided to classify said printing devices, and selector means operable in timed relation with the operating means to regulate operation of said operative means in accordance with the classification of the printing device disposed at selector position and embodying detecting means operable independently of the operating means and including a source of light positioned on one side of said printing device guideway, and light sensitive means positioned on the other side of said printing device guideway and adapted to be influenced by light from said source, the identifying means on the printing device at selector position regulating the passage of light to said light sensitive means and thereby determining the operation of said selector means.
19. In a printing machine, operating means, operative means operated by said operating means, a printing device guideway including a selector position, means sequentially moving printing devices through said guideway and the selector position therein, said printing devices having a plurality of identifying means positions distributed thereover whereat identifying means may be provided to classify said printing devices, and selector means operable in timed relation with the operating means to regulate operation of said operative means in accordance with the classification of the printing device disposed at selector position and embodying detecting means operable independently of the operating means and including a source of light positioned on one side of said printing device guideway, light sensitive means positioned on the other side of said printing device guideway and adapted to be influenced by light from said source, the identifying means on the printing device at selector position regulating the passage of light to said light sensitive means and thereby determining the operation of said selector means, and means controlling the passage of light to the identifying means on the printing device at selector position whereby only predetermined of said identifying means are effective in determining the operation of said selector means.
20. In a printing machine, operating means, operative means operated by said operating means, a printing device guideway including a selector position, means sequentially moving printing devices through said guideway and the selector position therein, said printing devices having a plurality of identifying means positions distributed thereover whereat identifying means may be provided to classify said printing devices, and selector means operable in timed relation with the operating means to regulate operation of said operative means in accordance with the classification of the printing device disposed at selector position and embodying detecting means operable independently of the operating means and including a source of light, light sensitive means adapted to be influenced by light from said source, means directing a beam of light from said source to selector position and concentrating said beam on the identifying means positions on the printing device at selector position, and means to control the passage of the beam of light to the identifying means positions on the printing device at selector position whereby only predetermined of said positions are effective in the regulation of the operation of said operative means.
21. In a printing machine which has a printing device guideway including a selector position, means sequentially moving printing devices through said guideway and the selector position therein, said printing devices having a plurality of identifying means positions distributed thereover whereat identifying means may be provided to classify said printing devices, a plurality of receptacles to receive said printing devices after passage thereof through selector position, and means for selectively diverting said printing devices into the receptacles, the combination of means to regulate operation of the printing device diverting means in accordance with the classification of the printing device disposed in selector position and embodying detecting means including a source of light, light sensitive means adapted to be influenced by light from said source under control of the

identifying means on the printing devices, and means to control the passage of light to the identifying means positions on the printing device at selector position whereby only the identifying means at selected of said positions effect operation of said printing device diverting means in a predetermined manner.

22. In a printing machine which has a printing device guideway including a selector position, means sequentially moving printing devices through said guideway and the selector position therein, said printing devices having a plurality of identifying means positions distributed thereover whereat identifying means may be provided to classify said printing devices, a delivery chute through which said printing devices normally pass, and means for diverting selected printing devices from said chute, the combination of means to regulate the operation of the diverting means in accordance with the classification of the printing device disposed in selector position and embodying detecting means including a source of light, light sensitive means adapted to be influenced by light from said source under control of the identifying means on the printing devices, and means to control the passage of light to the identifying means positions on the printing device at selector position whereby only the identifying means at selected of said positions effect operation of said diverting means.

23. In a printing machine which has a printing device guideway including a selector position, means sequentially moving printing devices through said guideway and the selector position therein, said printing devices having a plurality of identifying means positions distributed thereover whereat identifying means may be provided to classify said printing devices, a delivery chute through which said printing devices normally pass, a branch chute, means for diverting selected printing devices into said branch chute, and separate receptacles to receive said printing devices from the respective chutes, the combination of means to regulate the operation of the diverting means in accordance with the classification of the printing device disposed in selector position and embodying detecting means including a source of light, light sensitive means adapted to be influenced by light from said source under control of the identifying means on the printing devices, and means to control the passage of light to the identifying means positions on the printing device at selector position whereby only the identifying means at selected of said positions effect operation of said diverting means.

24. In a printing machine, a printing device guideway including a selector position, means sequentially moving printing devices through said guideway and the selector position therein, said printing devices having a plurality of identifying means positions distributed thereover whereat identifying means may be provided to classify said printing devices, a plurality of receptacles to receive said printing devices after movement thereof from said guideway, a selector mechanism cooperating with the printing device at selector position to detect the classification thereof, means controlled by said selector mechanism to selectively direct said printing devices according to the classification thereof into the respective receptacles after movement thereof from said guideway, said selector mechanism embodying detecting means including a

source of light, light sensitive means adapted to be influenced by light from said source, means directing a beam of light from said source to selector position and concentrating said beam on the identifying means positions on the printing device at selector position, and means to control the passage of the beam of light to the identifying means positions on the printing device at selector position whereby only selected of said positions are effective in the regulation of the operation of said selector mechanism.

25. In a printing machine, a printing device guideway including a selector position, means sequentially moving printing devices through said guideway and the selector position therein, said printing devices having a plurality of identifying means positions distributed thereover whereat identifying means may be provided to classify said printing devices, a pair of receptacles to receive said printing devices, a pair of chutes leading to said receptacles, a gate to direct said printing devices in the respective chutes, a selector mechanism cooperating with the printing device in selector position to detect the classification of the printing device at selector position, means controlled by said selector mechanism to actuate said gate according to the classification of the printing device at selector position, said selector mechanism embodying a detecting means including a source of light, light sensitive means adapted to be influenced by light from said source, means directing a beam of light from said source to selector position and concentrating said beam on the identifying means positions on the printing device at selector position, and means to control the passage of the beam of light to the identifying means positions on the printing device at selector position whereby only selected of said positions are effective in the regulation of the operation of said selector mechanism.

26. In a printing machine, a printing couple, means for moving a web through said printing couple whereby impressions may be made at spaced intervals on one face thereof, means for severing sheets from the web intermediate the impressions, a platen, means for carrying the severed sheets into printing position below said platen, means for moving printing devices into printing position whereby impressions may be made on said sheets from said printing devices, and means for rendering said platen, said carrying means, severing means and web moving means inoperative when predetermined of the printing devices move into printing position and comprising a selector mechanism embodying detecting means including a source of light, light sensitive means adapted to be influenced by light from said source under control of identifying means on the printing devices, said printing devices having a plurality of identifying means positions distributed thereover whereat the identifying means may be selectively provided, and means to control passage of light to the identifying means positions on the printing device at selector position whereby only the identifying means at selected of said positions effect operation of said selector mechanism.

27. In a printing machine having means for moving a web thereto, means for severing sheets from said web, a platen, means for carrying the sheets past the platen, means for stopping sheets in position relative to said platen, means for moving printing devices having a plurality of identifying means positions distributed thereover

whereby identifying means may be provided to classify printing devices into printing position relative to said platen whereby impressions may be made from said printing devices on said platen, and means for rendering said platen, sheet stopping means, sheet carrying means, severing means and web moving means inoperative when predetermined of said printing devices are moved into printing position and comprising a selector mechanism embodying detecting means including a source of light, light sensitive means adapted to be influenced by light from said source under control of identifying means on the printing devices, said printing devices having a plurality of identifying means positions distributed thereover whereat the identifying means may be selectively provided, and means to control passage of light to the identifying means positions on the printing device at selector position whereby only the identifying means at selected of said positions effect operation of said selector mechanism.

28. In a printing machine for making impressions on bill sections, comprising a main body and one or more stubs, the combination of printing means including a form for making an impression in each printing operation thereof on each bill section, impression means, means for moving printing devices having a plurality of identifying means positions distributed thereover whereat identifying means may be provided to classify said printing devices into printing position relative to the impression means whereby impressions may be made from said printing devices on one face of the main body and stubs of each bill section separately, means cooperating with the printing means for feeding bill sections through the machine, and means for rendering printing means, the impression means and the feeding means inoperative when predetermined printing devices move into printing position and comprising a selector embodying detecting means including a source of light, light sensitive means adapted to be influenced by light from said source, means

directing and concentrating a beam of light from said source on the identifying means positions on a printing device in a predetermined position in the machine, and means to control the passage of light to the identifying means positions on the printing device at said positions whereby only selected of the identifying means positions are effective in the regulation of the operation of said selector mechanism.

29. In a printing machine for making impressions on bill sections comprising a main body and one or more stubs, the combination of printing means including a form for making an impression in each printing operation thereof on each bill section and adapted to feed the bill sections through the machine during the printing operations thereof, impression means, means for moving printing devices having a plurality of identifying means positions distributed thereover whereat identifying means may be provided to classify said printing devices into printing position relative to the impression means whereby impressions may be made from said printing devices on one face of the main body and stubs of each bill section separately, means cooperating with the printing means for feeding bill sections through the machine, and means for rendering printing means, the impression means and the feeding means inoperative when predetermined printing devices move into printing position and comprising a selector embodying detecting means including a source of light, light sensitive means adapted to be influenced by light from said source, means directing and concentrating a beam of light from said source on the identifying means positions on a printing device in a predetermined position in the machine, and means to control the passage of light to the identifying means positions on the printing device at said positions whereby only selected of the identifying means positions are effective in the regulation of the operation of said selector mechanism.
